GAS TURBINE

Joseph A. Rawlins, Tenafly, N. J., assignor, by
mesne assignments, to The Sperry Corporation,
a corporation of Delaware

Original application October 5, 1945, Serial No.
620,523, now Patent No. 2,511,543, dated June
13, 1950. Divided and this application Sep-
tember 27, 1947, Serial No. 776,559

2 Claims. (Cl. 253—2)

1

This invention relates to gas turbines and more particularly to mechanism for imparting a limited axial oscillating movement to a turbine shaft.

An object of the invention is to provide mechanism responsive to the gas discharge pressure from the turbine, for automatically producing the oscillating movement.

Another object is to provide means for controlling the axial position of the turbine shaft without physical frictional contact with the rotating parts.

Another object is to provide a novel and improved device of the type above indicated.

Various other objects and advantages will be apparent as the nature of the invention is more fully disclosed.

This application is a division of my co-pending application, Serial No. 620,523, filed October 5, 1945, for Gas Lubricated Bearing, now Patent No. 2,511,543, issued June 13, 1950.

The present invention is particularly applicable to spindles for high speed tools such as small diameter grinding wheels which may operate at speeds of the order of 50,000 R. P. M. The bearing may have a clearance of the order of .0001 inch so as to position the tool accurately and cause it to operate without wobble or side play.

In accordance with the present invention the gas is discharged at the two sides of the turbine rotor into channels formed between the rotor and a pair of side plates. The relative gas pressures on the two sides of the rotor are a function of the clearance of the side plates. When the clearances are equal the pressure on the two sides of the rotor is equalized and no axial movement takes place. However, by shifting one of the side plates so as to increase or decrease the clearance the pressure balance is upset and the differential air pressure acting on the two sides of the rotor causes axial movement thereof. In one embodiment the position of the side plates is varied when the rotor reaches its limiting axial position so as to automatically cause the rotor to shift axially first in one direction and then in the other.

Although the novel features which are believed to be characteristic of this invention are pointed out more particularly in the claims appended hereto, the invention itself may be better understood by referring to the following description taken in connection with the accompanying drawings in which specific embodiments thereof have been set forth for purposes of illustration.

Fig. 1 is an end elevation of an air-lubricated

spindle including mechanism for causing axial oscillation of the spindle;

Fig. 2 is a side elevation of the spindle of Fig. 1;

Fig. 3 is a vertical longitudinal section thereof taken on the line 3—3 of Fig. 1; and

Fig. 4 is a section similar to Fig. 3 but showing the spindle in a different axial position.

Referring to the drawings, the invention is shown as applied to a spindle 10 carrying a tool, shown as a grinding disc 11, mounted on a shank 12 which is secured to the spindle 10 by suitable means shown as a set screw 13. The spindle 10 is provided with an enlarged cylindrical bearing section 14 which is journaled in bearings surfaces 15 and 16 formed in upper and lower bearing blocks 17 and 18, respectively.

The lower bearing block 18 constitutes a fixed support and is mounted by any suitable means not shown. The upper bearing block 17 is accurately positioned transversely of the lower bearing block 18 between clips 19. Studs 20 are secured in the lower bearing block 18 and extend through holes in the upper bearing block 17 so as to position the upper bearing block axially relative to the lower block and to allow vertical movement of the upper block. The upper bearing block 17 is yieldably held against the lower bearing block 18 by means of slotted leaf springs 21 which engage grooves 22 in the studs 20.

The bearing blocks 17 and 18 are formed with cylindrical chambers 25 extending axially of the blocks between the bearing surfaces 15 and 16. The radius of the chambers 25 is such as to provide substantial clearance for the bearing section 14 of the spindle. Horizontal slots 26, formed half and half in the two bearing blocks, extend from the chambers 25 to the outside of the blocks between shoulders 27. The shoulders 27 form the contacting surfaces for the two bearing blocks and are accurately finished to determine the minimum bearing clearance. The clearance between the bearing section 14 and the bearing surfaces 15 and 16 is of the order of .0001 inch when the shoulders 27 are in contact.

This clearance, however, is permitted to be increased by separating the bearing blocks 17 and 18 against the pressure of the springs 21.

Axial channels 28 (Fig. 1) are formed half and half in the bearing blocks 17 and 18 along the parting line so that the bearing surfaces 15 and 16 are removed for a short distance each side of the parting line.

The spindle 10 is shown as rotated by an air turbine comprising a rotor 30 enclosed in a housing 31 and having suitable driving vanes 32. The

housing 31 includes an air chamber 33 and admission ports 34 by which air is supplied to the vanes 32 in the usual manner for causing rotation of the rotor. The rotor 30 is mounted upon an extension 35 of the spindle 10 which is of reduced section, and is held against the enlarged bearing section 14 by means of an annular sleeve 37 which is mounted on the extension 35 of the spindle and has an annular rim 38 of the same diameter as the bearing section 14. Air is discharged from the turbine through openings 39 formed in the housing 31 around the rim 38 and around the bearing section 14. Baffle plates 40 and 82 are spaced from the two sides of the housing 31 in a manner to control the exhaust air pressure on the two sides of the rotor.

A disc 45 is attached to the end of the extension 35 by means of a screw 46. The housing 31 is secured by a screw 70 to a slide 61. The slide 61 is provided with inclined surfaces 62 which are slidably held in gibs 63 to permit axial adjustment. The slide 61 is secured in adjusted position by means of a clamping screw 64. The slide 61 is mounted for adjustment by means of an adjusting screw 65 which is threaded in a bracket 66 formed as a part of the lower bearing block 18 and is adjusted by a hand knob 67. A spring 68 holds the slide 61 against the end of the screw 65. Compressed air is supplied to the turbine through a duct 69.

The disc 45 is engaged by fingers 75 and 76 of a yoke 77 which is pivoted on a bracket 78 carried by an arm 60 attached to the slide 61. The plate 40 is shown as rigidly secured by screws 80 to the housing 31. The other plate 82, however, is loosely held on pins 83 and is hung from a supporting pin 84 so that the plate 82 may pivot about the pin 84 and allow the lower portion of the plate to approach or recede from the housing 31.

The position of this lower portion of the plate 82 is controlled by an arm 85 carried by the yoke 77 and engaging a cam plate 86 attached to the plate 82 and arranged so that when the spindle 10 is moved to the right as shown in Figs. 2 and 3 the disc 45 engages the finger 76 of the yoke 77 and causes pivotal movement of the yoke which retracts the arm 85 from the cam 86 and leaves the plate 82 free to swing away from the housing 31. When the spindle 10 is in its left-hand position as shown in Fig. 4, the disc 45 engages the finger 75 of the yoke and causes pivotal movement of the yoke to bring the arm 85 into engagement with the cam plate 86 thereby forcing the plate 82 toward the housing 31. The arrangement is such that with the plate 82 in the position shown in Fig. 4 the clearance between the plate 82 and the housing 31 is less than the clearance between the stationary plate 40 and the housing 31, but with the plate 82 released as shown in Figs. 2 and 3 the clearance between the plate 82 and the housing 31 is greater than that between the stationary plate 40 and the housing 31.

In the operation of this device, the spindle 10 is rotated by the compressed air turbine in a manner which will be readily understood. The lubricant for the bearing surfaces 15 and 16 constitutes air which is compressed between the bearing surfaces 15 and 16 and the bearing section 14 of the spindle 10 due solely to the relative rotation of the parts. The air is accordingly maintained at a pressure which is above that of the surrounding atmosphere due solely to the rotation of the parts themselves.

The air pressure on the two sides of the rotor 30 is controlled by the clearance between the plates 40 and 82, respectively, and the housing 31 because the air discharged from the turbine passes outwardly through the openings 39 and then is exhausted to atmosphere through the passages between the plates 40 and 82, respectively, and the housing 31, and is also exhausted between the plates 40 and 82 and the surface of the bearing section 14 and of the rim 38. When these clearances are equal the air pressures on the two sides of the rotor are equalized and the rotor remains in a central position. However, when the plate 82 is released as in Figs. 2 and 3, the pressure on the left-hand side of the rotor becomes less than the pressure on the right-hand side of the rotor and the latter is driven by this pressure differential toward the left-hand side of the housing 31 into the position shown in Fig. 4. When this position is reached, the arm 85 is actuated to engage cam 86 and shift the plate 82 toward the housing 31 so that the clearance between the plate 82 and the housing 31 becomes less than that between the plate 40 and the housing 31. Air pressure is thus built up on the left-hand side of the rotor which causes the rotor to shift axially to the right-hand side of the housing into the position indicated in Fig. 3. In that position the arm 85 is again actuated to release the plate 82 and the operation is repeated.

The turbine rotor 30 and the spindle 10 are thus caused to oscillate in an axial direction. Such axial operation of the grinding disc 11 may be useful, for example, in polishing or grinding surfaces to a smooth finish where it is desired to avoid any marks which might otherwise be produced by the grinding wheel itself.

Although certain specific embodiments of the invention have been shown for purposes of illustration, it is to be understood that the invention is capable of various uses and that changes and adaptations may be made therein as will be readily apparent to a person skilled in the art. The invention is only to be restricted in accordance with the scope of the following claims.

What is claimed is:

1. In combination with a spindle mounted for free rotary and axial movement, a gas driven turbine having a rotor with peripheral vanes mounted on said spindle to rotate the same, a turbine housing having a peripheral wall and side walls forming gas chambers on each side of said rotor, ports supplying gas peripherally to said vanes, said side walls having gas discharge ports from each of said chambers, plates mounted respectively over each of said side walls and spaced therefrom to provide passages for the exhaust of gas discharged from said discharge ports, one of said plates being adjustable toward and from its side wall to vary said passage and produce a pressure differential on the two sides of said rotor and effect axial movement of the rotor and spindle, a member mounted for back-and-forth movement and disposed to engage and position said one plate relative to its side wall, and actuating means on the spindle operatively engageable with the member.

2. In combination with a spindle mounted for free rotary and axial movement, a gas driven turbine having a rotor with peripheral vanes mounted on said spindle to rotate the same, a turbine housing having a peripheral wall and side walls forming gas chambers on each side of said rotor, ports supplying gas peripherally to said vanes, said side walls having gas discharge ports

from each of said chambers, plates mounted respectively over each of said side walls and spaced therefrom to provide passages for the exhaust of gas discharged from said discharge ports, one of said plates being adjustable toward and from its side wall to vary said passage and produce a pressure differential on the two sides of said rotor and effect axial movement of the rotor and spindle, a bell-crank oscillatory member having a cam on one arm engageable with the said one plate as the member oscillates to control its spacing from its side wall, and an actuating pro-

jection on the spindle engageable with the other arm to oscillate the member.
